UNITED STATES PATENT OFFICE.

FRANK. J. HERRICK, OF NEW BRITAIN, CONNECTICUT.

DESIGN FOR A BELT-CLASP.

SPECIFICATION forming part of Design No. 20,110, dated August 26, 1890.

Application filed December 30, 1889. Serial No. 335,416. Term of patent 7 years.

To all whom it may concern:

Be it known that I, FRANK. J. HERRICK, a citizen of the United States, residing at New Britain, in the county of Hartford and State 5 of Connecticut, have invented and produced a new and original Design for Belt-Clasps, of which the following is a specification, reference being had to the accompanying drawings, forming a part thereof.

10 Figure 1 is a front view of a belt-clasp, showing my design. Fig. 2 is a detail edge view of the same.

The leading feature of my design consists in the curved figure of a dolphin more or less 15 conventionally treated as to shape and surface ornamentation and shown as extending between the side parts of a belt-clasp.

A subordinate feature of the design consists of the curved figure of the dolphin and 20 the belt-loop forming the frame of oblong shape, and the surface bearing indentations that show in relief a conventional treatment of a leaf that is also brought out by the irregular bounding-lines of the frame.

25 The letter *a* denotes the oblong frame referred to; *b*, one of the scrolls that is repeated in the composition of the design; *c*, the corner-piece, also repeated in making up the design of the frame as a whole; *d*, the cross-bar, and *g*

an eye that is grasped in the mouth of the 30 dolphin *f*, the tail of which is curved backward and passes through an open eye *h* in the frame *a'*, that is a duplicate of the frame *a* as to outline and ornamentation.

The design as a whole, so far as the subordinate feature is concerned, represents the hook-shaped fish extending between two frames of oblong shape and irregular outline, the surface of the frames showing in alternation the raised and depressed features that, 40 together with the irregular bounding-edges, make up the scroll effect based on the arbitrary or conventional treatment of a leaf springing from curved lines at a central point.

45 What I claim is—

The design for a belt-clasp herein shown and described, the same comprising the curved figure of a dolphin extending between the side parts of two loops, the said loops each comprising an oblong frame with irregular bounding-lines and irregular surface formed in curved scrolls representing the conventional treatment of a leaf, as shown.

FRANK. J. HERRICK.
